GAGE,

APPLICATION FILED MAY 15, 1915.

1,181,173.

Patented May 2, 1916.

2 SHEETS—SHEET 2.

FIG. 4.

FIG. 6

A cross-sectional diagram of a cylindrical component. The outermost layer is labeled 19. Inside is a layer labeled 16. The central tube is labeled 11. The next layer in is labeled 120. The innermost layer is labeled 15. A vertical line labeled 'c' is shown. A small circular feature is labeled 17. A larger, irregularly shaped feature is labeled 18. The innermost boundary is labeled 19. At the very bottom, a layer is labeled 12.

FIG. 5.

FIG. 8

A diagram showing a curved, irregular shape, possibly a piece of metal or a casting. The number '12' is written near the top left, and '219' is written near the bottom right. A small circle is located near the top right. The shape has a jagged, broken edge on the right side.

UNITED STATES PATENT OFFICE.

FREDERICK SCHUBERT, OF SELLERSVILLE, PENNSYLVANIA.

GAGE.

1,181,173.

Specification of Letters Patent.

Patented May 2, 1916.

Application filed May 15, 1915. Serial No. 28,252.

To all whom it may concern:

Be it known that I, FREDERICK SCHUBERT, a citizen of the United States, residing at Sellersville, in the county of Bucks and State of Pennsylvania, have invented certain new and useful Improvements in Gages, of which the following is a specification.

My invention relates to gages and similar instruments and it has particular relation to improved means for mounting the face glasses in such instruments whereby the same will be less liable to breakage in transportation and in use.

My invention contemplates improved means for providing a resilient support for said face glass whereby the glass will be permitted to be depressed slightly in the event of a light blow or pressure being brought to bear on any portion thereof.

Heretofore in the mounting of the face glasses of pressure gages and similar instruments, it has been usual to support the glass at the periphery thereof more or less rigidly so that in the event of a light blow or pressure upon any portion of the glass the same would be cracked or broken. Numerous means for overcoming this difficulty have been tried such as the employment of com-

pressible gaskets and in some instances separate springs have been employed at various points about the periphery of the glass. Where such springs have been employed in the construction heretofore designed, the

arrangement was more or less clumsy and required considerable space beneath the retaining ring, resulting in an inelegant design and appearance of the face of the gage. My invention contemplates an integral device

adapted to be mounted beneath the periphery of the face glass occupying a small space and also having means whereby the glass will be prevented from being forced entirely down in contact with the dial plate which

would result in damage either to the glass itself or to the needle or other indicating mechanism which is arranged between said dial plate and the glass.

A modified form of my invention contemplates the construction of the resilient supporting means and the limiting means integral with the dial plate itself.

The nature and characteristic features of my invention will be more readily understood from the following description taken

in connection with the accompanying drawings forming part hereof, in which—

Figure 1 is a front elevation of a pressure gage with the face glass and its retaining ring removed and showing the device for supporting the face glass and embodying the main features of my present invention mounted therein; Fig. 2 is a perspective view of the supporting ring detached; Fig. 3 is a fragmentary sectional view of the gage casing taken approximately on the line 3—3 of Fig. 1; Fig. 4 is a view similar to Fig. 1 but showing a modified form of my invention; Fig. 5 is a view similar to Fig. 2 illustrating the modified form of the ring shown in Fig. 4; Figs. 6 and 7 are sectional views taken respectively on the lines 6—6 and 7—7 of Fig. 4; Fig. 8 is a view similar to Fig. 2, but illustrating a modified form of my invention wherein the spring supporting means is constructed as an integral portion of the dial plate; and Fig. 9 is a fragmentary perspective view of said dial plate provided with the integral spring supporting means.

Referring now more particularly to Figs. 1 to 3 of the drawings, the gage or other instrument may be of any suitable construction but in the particular embodiment of my invention therein shown, comprises a cup-like casing 10 within which the Bourdon tube 11 is mounted. The instrument is provided at the front with a dial plate 12 suitably marked for indicating changes in pressure by means of an indicating needle 13 which is mounted on the stud shaft 14 which projects through the dial plate and is controlled by the Bourdon tube 11 in the usual manner and by means of the usual mechanism, not shown. Mounted in front of the dial plate 12 is the glass face plate 15 which is retained in position by means of a peripheral retaining ring 16 which may also be of any preferred type, and which may be secured to the gage casing 10 in any suitable manner. It should be understood that a space or chamber 17 is provided between the dial plate 12 and the face glass 15 in which space the needle 13 is mounted for indicating, by changes in its position, variations in pressure within the tube 11.

Mounted beneath the edge of the face glass 15, between it and the peripheral portion of the dial plate 12, is a ring 18 which is provided with a plurality of integral

struck-up portions 19 forming springs which project toward the glass contacting therewith and holding the same normally against the inside of the retaining ring 16. The struck-up spring members 19 are spaced about the ring 18 at regular intervals, as shown in Figs. 1 and 3 of the drawings. The ring 18 is also provided with a peripheral rim 20 extending a sufficient distance to form a stop or limit beyond which the face glass may not be depressed so as to come in contact with the indicating needle 13 or its supporting shaft 14 as otherwise said needle or the face glass would be damaged through the contacting of these parts.

In the form of the invention in Figs. 4 to 7 of the drawings the rim 20 is omitted and in lieu thereof and arranged at corresponding intervals respectively between each of said struck-up springs 19, there is provided a plurality of projections 120 preferably formed by striking up portions of the metal of the ring and curling the same, as clearly shown in Fig. 5 of the drawings. These projections 120 serve to prevent the glass from being entirely depressed against the dial plate so that the same will not be able to contact with the needle 13 or the stud 14 upon which said needle is mounted. It will be seen that in this form of the invention the portions of the ring 18 between adjoining projections 120 also form spring bridges which coact with the projecting fingers 19 so that when pressure is brought to bear or a blow is delivered against the face glass, the same will be permitted to be depressed sufficiently to relieve the pressure or the force of the blow thus obviating a considerable amount of the breakage which has been usual heretofore both in transportation and in the use of the instrument.

With either of the arrangements as above set forth the supporting ring 18 will be substantially hidden beneath the retaining ring 16 permitting this retaining ring to be made of relatively small dimension and of neat design yet accomplishing the desired purpose.

In Figs. 8 and 9 there is shown a further modified form of the invention in which the ring 18 is dispensed with and in lieu thereof, the margin of the dial plate 12 is provided with spring fingers 219 and projections 220 which correspond in function respectively to the spring fingers 19 and the rim 20 or projections 120 on said ring 18.

Having thus described the nature and characteristic features of my invention, what I claim as new and desire to secure by Letters Patent is:—

1. In a gage or similar instrument, a casting, a face glass, external retaining means for said face glass, and a device mounted beneath said face glass having a plurality of integral spring members supporting said glass at the edge thereof, and having integral means for limiting the extent of depression of said glass against the tension of said spring members.

2. In a gage or similar instrument, a casting, a face glass, external retaining means for said face glass, a ring mounted beneath said glass at the edge thereof having a plurality of integral spring members for supporting said glass, and provided with integral means for limiting the extent of depression of said glass against the tension of said spring members.

3. In a gage or similar instrument, a casting, a face glass, external retaining means for said face glass, a ring mounted beneath said glass at the edge thereof having a plurality of integral spring members for supporting said glass and provided with means for limiting the extent of depression of said glass against the tension of said spring members, said means comprising an integral extending rim portion.

In testimony whereof, I have hereunto signed my name in the presence of two witnesses.

FREDERICK SCHUBERT.
